DOOR LOCK

Peter Aguayo-Delgado, Box 235, Planetarium Station,
New York, N.Y.

Filed Feb. 15, 1965, Ser. No. 83,815

Term of patent 7 years

(Cl. D50—5)

FIG. 2 is a front elevational view thereof,
FIG. 3 is a side elevational view thereof, and
FIG. 4 is a perspective view of the opened box.
I claim:
The ornamental design for a door lock, as shown.
